WILLIAM E. LUNDEGREEN, OF WORCESTER, MASSACHUSETTS, ASSIGNEE TO CROMPTON & KNOWLES LOOM WORKS, OF WORCESTER, MASSACHUSETTS, A CORPORATION OF MASSACHUSETTS

TAKE-UP FOR LOOMS

Application filed September 28, 1939. Serial No. 395,988.

This invention relates to improvements in take-ups for looms and it is the general object of the invention to provide mechanism wherein a very wide range of picks per inch may be secured.

In one well-known form of take-up the rocker foot to which the lay is secured and by means of which it is pivoted has a slot radial with respect to the rocker shaft. A 10 vertically reciprocating rod is mounted on a stud adjustable along the slot, the rod being connected at its upper end to some form of pawl to actuate the ratchet wheel of a train of take-up gears. I find in constructions of 15 this type that it is difficult to weave cloth having a large number of picks to the inch, due to the fact that the stud can not be moved near enough to a vertical line passing through the rocker shaft to provide very small movements. It is a further object of my present 20 invention to provide the rocker foot with a slot out of horizontal alignment with the rocker shaft axis, preferably above the latter, and extending over said shaft so that if de- 25 sired the amount of vertical motion on the reciprocating rod may be made to approach zero as a limit.

On certain types of looms, for instance those weaving narrow ware goods having a 30 large number of picks to the inch, it is desirable to be able to vary the time in the cycle of the loom at which the take-up shall have its forward movement. In many looms the take-up is actuated when the lay is on its for- 35 ward stroke with the harnesses practically in mid-position to lessen the strain on the warp and at the time the reed moves the cloth forward, thereby lessening the strain on the take-up mechanism. It is desirable in other 40 instances to cause the take-up to operate at some time other than the beating-in of the filling so as not to interfere with the placing of the latter in the fabric. It is an important object of my present invention to provide a 45 take-up of the type previously referred to wherein the slot which is movable with the rocker foot extends on both sides of a vertical line passing through the axis thereof, thereby permitting the feeding movement of 50 the upright reciprocating rod to occur when

the lay is moving either forwardly or rearwardly.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is an end elevation of the forward portion of a loom having my invention applied thereto,

Fig. 2 is a front elevation taken in the direction of arrow 2, Fig. 1,

Fig. 3 is a detailed horizontal section taken on line 3—3 of Fig. 1, and

Fig. 4 shows a portion of the structure shown in Fig. 1 but with the parts moved so as to effect feeding at a different point in 70 the cycle of the loom.

Referring to the drawings, I have shown a loomside 10 having a lay 11 mounted on a sword 12 having a bearing 13 mounted on a rocker pin or shaft 14.

The take-up mechanism includes a train of mechanism having a ratchet wheel 15 mounted on a stud 16. A lever 17 is pivoted to move about the stud 16 and has a slot 18 through which extends a stud 19 adjustable 80 along the length of said slot to be at varying distances from the axis of the ratchet wheel. A feed pawl 20 is pivoted to the lever 17 as at 21 and when drawn downwardly by means of a reciprocating rod 22 connected to the stud 19 will cause a partial rotation of the ratchet wheel 15. On the reverse stroke of the working or feeding pawl 20 a hold pawl 23 pivot- 85 ed about a fixed axis 24 will engage the ratchet to hold the same against retrograde move- 90 ment.

It is to be understood that the structure shown at the upper part of Fig. 1 which causes rocking movement of the ratchet 15 forms no particular part of my present invention and is set forth herein to illustrate a take-up device which will be operated by the reciprocating rod 22. Although the downward motion of said rod is used herein to effect feeding of the take-up if desired the 100

upward movement may effect this result, as will be apparent to those skilled in the art.

The matter thus far described is of common construction and forms no part of my present invention, being similar to the form of take-up employed on silk looms.

In carrying my invention into effect I form the rocker foot R with a web 30 preferably integral therewith and extending thereabove. In said web I form a horizontal slot 31 through which extends a stud 32. The latter is held in place by a nut 33 on one side of the web and on the other side of the latter said stud forms a pivotal support for the lower end of the rod 22. As shown in Fig. 1 the slot 31 extends to the right and also to the left of a vertical line passing through the axis of the rocker shaft 14.

In operation, the lay will move back and forth by means of mechanism not shown to cause a slight rocking movement of the foot R, thus causing a vertical movement of the rod 22. As shown in Fig. 1 when the lay moves forwardly the rod 22 will be lowered because of the fact that the stud 32 is to the right of and in front of shaft 14, so that advance movement of the take-up will occur when the lay is advancing. As shown in Fig. 4, however, the stud 32 is at the left end 30 of the slot 31 so that the rod 22 has a downward or feeding movement when the lay is moving rearwardly. In this way, by varying the location of the stud 32 along the slot 31, it is possible to effect feeding movement 35 of the take-up when the lay is moving either forwardly or rearwardly.

It is also to be understood that by varying the position of the stud 32 the amount of the feed can be varied. When the stud is at the extreme right end of the slot the feed pawl is given its largest motion in a feeding direction when the lay is advancing. If a smaller motion is required the stud is moved to a position nearer a vertical line passing 45 through the shaft 14 and can approach such a position because of the fact that the slot lies entirely above the rocker shaft. A similar adjustment may be had when the stud is on the other side of the rocker shaft.

From the foregoing it will be seen that I have provided a very simple form of take-up drive wherein the extent of motion of the feeding pawl can be varied from zero to the maximum in either direction, whereby feeding 55 may occur either when the lay is moving forwardly or rearwardly. It will further be seen that for either setting the degree of motion can be varied because of the fact that the web 30 extends upwardly from the shaft 14 to permit the stud 32 to come nearer vertical alignment with the axis of the lay than is possible under present constructions.

Having thus described my invention it 60 will be seen that changes and modifications

may be made therein by those skilled in the art without departing from the spirit and scope of the invention and I do not wish to be limited to the details herein disclosed, but what I claim is:

1. In a take-up for a loom provided with a member having a feeding movement in one direction and a lay to move back and forth, a rocker foot for the lay, a pivotal support for the foot, means moving with the rocker foot defining a slot out of horizontal alignment with the axis of the lay, and connections between the feeding member and the rocker foot including an element extending through the slot to be held at any one of a plurality of positions along the slot, said slot extending to a position substantially over the axis of the lay, the slot extending on both sides of the axis of the lay, whereby advance movement of the feeding member may be effected during the forward or backing movement of the lay. 70

2. In a take-up for a loom provided with a member having a feeding movement in one direction and a lay to move back and forth, a rocker foot for the lay, a pivotal support for the foot, means carried by the rocker foot defining a slot extending forwardly and rearwardly of a vertical line passing through the axis of the pivotal support for the foot, and connections between the feeding member and said means including an element movable in the slot to be secured thereto in any position between the ends of the slot on either side of said vertical line, whereby the take-up may have a feeding movement when the lay is moving either rearwardly or forwardly and wherein the degree of movement may vary from zero to a finite quantity. 85

3. In a take-up for a loom provided with a member having a feeding movement in one direction and a lay to move back and forth a rocker foot to support the lay, a rocker shaft about the axis of which the foot and lay move, a web integral with the rocker foot and extending above the shaft, said web having a slot therein which extends in front of and behind a vertical line passing through the axis of the rocker shaft, a stud passing through the slot and adjustable therealong to be secured to the rocker foot in any one of a plurality of positions with respect to the said vertical line on either side thereof, and a connector interposed between the stud and the feeding member, whereby said member can be given a feeding movement when the lay is moving either rearwardly or forwardly, the degree of movement being dependent upon the distance of the stud from the vertical line passing through the axis of the rocker shaft. 105

4. In a take-up for a loom, a member having a feeding movement in one direction, a periodically rocking element to move backwardly and forwardly about a pivot, driv- 110

ing means on the element to actuate the member and connections to operatively relate the member and means on either side of a vertical line passing through the pivot so that the means may drive the member on either the backward or forward movement of the rocking element.

5. In a take-up for a loom, a driven take-up roll moving member having a feeding movement in one direction, a driving member moving back and forth periodically and having a part movable toward and then from the driven member during a back and forth motion of the driving member and having 10 also a second part movable away from and then toward the driven member during the same back and forth motion of the driving member; and means to connect the driven member to either part of the driving member 15 to cause the driven member to have its feeding movement during either the back or forward movement of the driving member.

In testimony whereof I have hereunto affixed my signature.

25 WILLIAM E. LUNDGREN.
